UNITED STATES PATENT OFFICE.

MAX MEINKE, OF POLLNOW, GERMANY.

SPINNING APPARATUS.

Application filed May 11, 1925, Serial No. 29,578, and in Germany October 8, 1924.

This apparatus is intended for domestic use to be driven either by hand or foot or by means of a small motor. The apparatus is equipped with correspondingly simple appliances which are essentially distinguished in their construction and action from those used in spinning machinery for the manufacture of yarn in the factories, but, notwithstanding their simplicity they completely fulfil the desired purpose and yield a strong fibre of good quality, whether it be as a single thread or as a twisted thread. The apparatus is intended to co-operate with a small carding engine in which the material to be spun, which may be flax, cotton, wool or the like, is first worked up to a fleece. The fleece thus obtained is refined or attenuated by repeatedly passing through the carder before it passes to the actual spinning apparatus.

The invention is illustrated by way of example in the accompanying drawings wherein—

Figure 1 is a plan of the apparatus;

Figure 2 is a side elevation thereof;

Figure 3 is a vertical longitudinal section on the line III—III of Fig. 1 on a larger scale;

Figure 4 a longitudinal section through a detail, likewise on a larger scale;

Figure 5 a perspective view of a detail of the device illustrated in Figure 4 on a still larger scale and

Figure 6 a side elevation of a detail also on a larger scale.

The invention consists essentially in a web divider, a draft device and any desired spinning apparatus. The web divider consists of a series of individual belts 1 and 2; 3 and 4; and also 1^a and 2^a; 3^a and 4^a which work together in fours. The belts 1 and 2 run from a roller 5, over a top roller 6, under a bottom roller 7, through to a guide roller 8 and over a driving roller 9 arranged above the latter with a space between, and so back to the roller 5. These belts represent the top belts.

The bottom belts 1^a and 2^a run from a roller 10 arranged below the roller 5, always remaining substantially underneath the belts 1 and 2, and likewise run between the rollers 6 and 7 through to a roller 11 located in front of the roller 8 and from there back to the roller 10. The next pair of belts, namely 3 and 4 or 3^a and 4^a as the case may be, run in a similar manner, but with the difference that these four belts travel from the roller

5 or 10 first underneath a bottom roller 12 and over a top roller 13, as a result of which they are first shifted out of the plane of the belts 1, 2, 1^a and 2^a and are then guided back again into the said plane.

The next belts again run like the belts 1, 2, 1^a and so forth.

As a result of this arrangement the web that enters between the top and bottom belts as a coherent mass is first divided up into separate strips of web.

In certain of the rollers, for example the rollers 5, 10, 6, 12, 8 and 11, guiding grooves are provided which bring about in a special manner the collecting of the strips of web necessary for the formation of a roving. Each guiding groove 14 in the roller 5 takes up, for example, the belts 2 and 3, a further groove 15 takes up the belts 4 and 1 and so forth, in such a manner that between the grooves, guiding beads 16 are left standing which keep the belts 1 and 2, 3 and 4 at a distance from one another. The same remark applies to the belts 1^a, 2^a, 3^a and so forth which are likewise kept at the right distance from one another on the roller 10. By this distance the breadth of the strip of web is determined when the web is separated. On the roller 8 or 11, on the contrary, the belts 1 and 2 and also the belts 3 and 4 are united in a common groove 17, 18 and so forth, in each case. By this means the result is obtained that the original wide strip of web is narrowed during its passage through the web divider and guided together in order to be presented in this condition to a rubbing leather 19 and rubbing roller 20. The rubbing leather is in this case, preferably obliquely adjusted and designed to take off the web from the bottom belt, for which purpose it bears upon the latter. The rubbing roller 20 accordingly bears upon the top belt and takes off the strip of web from the latter.

It is essential that the belts 1, 2 or 3, 4 and so forth, on the other way between the roller 8 and 9, leave a small gap just sufficient to prevent the strip of web from being nipped between them and carried back with them and similarly also the belts 1^a, 2^a and 3^a, 4^a on the roller 11.

On the other hand there is, between the belts 2 and 3, as well as between the belts 3 and 4 and so forth, such a large gap at this point that even as a result of the rubbing movement no running together of the adjacent strips of web can take place.

The draft apparatus consists of a slide block 21 which can execute a reciprocating movement in guide bars 22. This slide block is preferably inclined somewhat obliquely upwards. In the slide block are journalled sleeves 23 with a clamping device 24 and are driven from a roller 25 by means of bands. The slide block consists of a stationary bar 27, in lateral guide blocks 26 and two movable rails 28 and 29 kept apart by means of distance pieces. The rails 28 and 29 can slide in the guide blocks for a purpose which will be hereinafter more fully set forth. The fixed rail 27 and the one movable rail 28 form the support for the sleeves 23. The sleeves comprise at the end, a transverse groove 30 extending to the base of the longitudinal bore with a rather wide cavity 31. In the sleeve is displaceably supported a resilient clamping piece 24 which reaches, by means of an arm 32, into the cavity 31 of the groove 30, and is rocked or shifted by means of an annular member 24^a or the like when the movable rails 28 and 29 are displaced, between which this annular member is arranged. By the arm 32 the rubber thread is nipped in the cavity 31 as indicated in Figure 4. The delivery aperture 33 for the thread F is preferably displaced somewhat to one side in order to improve the nipping action.

The slide block is moved by means of an eccentric 34 through a lever 35 with a guide rod 36 from any desired driving position so that it arrives uniformly, but somewhat more quickly than roving, travels upwards and returns quickly, for example, under the action of its own weight, as well as a returning spring 37, to its initial position.

The driving of the sleeves or of the roller 25 is effected by means of a band drive passing over guide rollers 38, 39 and 40 in such a manner that the roller 25 and with it the sleeves 23 rotate as the slide block rises, but stand still or go more slowly during the return of the slide block. By the sleeves so much twist is given to the clamped rubbed thread during the ascent of the slide block that a draft is possible. In the upper position of the slide block the clamping device is opened by shifting the movable rails 28 and 29 by means of rocking arms 41, and by raising the arm 32, and the thread is released so that the sleeves can return above the thread during the downward movement of the slide block.

The controlling of the clamping device is effected by means of two stops 42 and 43 which act upon an attachment 44 or a pawl 45 and thus impart a rotation to a shaft 46 carrying the rocking arms 41.

The fibre is supplied over doffers or stripper rollers to any desired spinning apparatus, for example, to a ring spinning frame with spindles 47, ring rail 48, traveller 49

and so forth. The ring rail is guided up and down in a known manner during the operation of the spinning apparatus. The twist arising as a result of the rotation of the sleeves is released again during the return of the slide block and during its ascent so that an untwisted fibre passes the doffers and this fibre first receives the correct twist from the spinning apparatus.

By disengaging the web divider and the draft device the apparatus may also be employed for twisting or doubling, the fibres to be twisted being passed directly into the doffers.

What I claim is:

1. In a spinning apparatus for working up material, pairs of coacting belts, each pair including an upper belt and a lower belt, means for guiding portions of each pair of belts in close parallel relation for receiving a fiber web therebetween, the guide means for certain of the pairs of belts being displaced with respect to the guide means of other of said pairs of belts to cause parts of the closely arranged belt portions of the several pairs to travel in different paths and thereby divide the fiber web into a plurality of strips. 80

2. In a spinning apparatus for working up material, pairs of coacting belts, each pair including an upper belt and a lower belt, means for guiding portions of each pair of belts in close parallel relation for receiving a fiber web therebetween, the guide means for certain of the pairs of belts being displaced with respect to the guide means of other of said pairs of belts to cause parts of the closely arranged belt portions of the several pairs to travel in different paths and thereby divide the fiber web into a plurality of strips, said guide means acting to guide groups of the upper and lower belts, respectively, in converging paths to reduce the width of the strip during travel of the belts. 100

3. In a spinning apparatus for working up material, pairs of coacting belts, each pair including an upper belt and a lower belt, means for guiding portions of each pair of belts in close parallel relation for receiving a fiber web therebetween, the guide means for certain of the pairs of belts being displaced with respect to the guide means of other of said pairs of belts to cause parts of the closely arranged belt portions of the several pairs to travel in different paths and thereby divide the fiber web into a plurality of strips, the upper and lower belts being arranged in groups and the belts of each group being widely spaced at one point in their length and extending in converging relation without contacting with each other to prevent nipping of the fiber strip. 115

4. In a spinning apparatus for working up material, pairs of coacting belts, each

- pair including an upper belt and a lower belt, means for guiding portions of each pair of belts in close parallel relation for receiving a fiber web therebetween, the guide means for certain of the pairs of belts being displaced with respect to the guide means of other of said pairs of belts to cause parts of the closely arranged belt portions of the several pairs to travel in different paths and thereby divide the fiber web into a plurality of strips, a rubbing leather and a rubbing roller, said leather and roller being arranged to act upon the fiber strips passing from between the belts.
5. In a spinning apparatus for working up material, pairs of coacting belts, each pair including an upper belt and a lower belt, means for guiding portions of each pair of belts in close parallel relation for receiving a fiber web therebetween, the guide means for certain of the pairs of belts being displaced with respect to the guide means of other of said pairs of belts to cause parts of the closely arranged belt portions of the several pairs to travel in different paths and thereby divide the fiber web into a plurality of strips, a rubbing leather and a rubbing roller, said leather and roller being arranged to act upon the fiber strips passing from between the belts, and a slide block draft device and spinning mechanism adapted to act upon the strip passing from the rubbing leather.
6. In a spinning apparatus for working up material, pairs of coacting belts, each pair including an upper belt and a lower belt, means for guiding portions of each pair of belts in close parallel relation for receiving a fiber web therebetween, the guide means for certain of the pairs of belts being displaced with respect to the guide means of other of said pairs of belts to cause parts of the closely arranged belt portions of the several pairs to travel in different paths and thereby divide the fiber web into a plurality of strips, a slide block arranged adjacent the belts, means for moving the slide block away from the belts and adapted to be moved in the opposite direction at greater velocity, rotatable tubes in said slide blocks, said tubes being adapted to receive the fiber strips, means embodied with said tubes for gripping the fiber strip and retaining it during the movement of the slide block away from the belts and drawing the strip and adapted, during movement of the slide block in the opposite direction to release the strip.
7. In a spinning apparatus for working up material, pairs of coacting belts, each pair including an upper belt and a lower belt, means for guiding portions of each pair of belts in close parallel relation for receiving a fiber web therebetween, the guide means for certain of the pairs of belts being displaced with respect to the guide means of other of said pairs of belts to cause parts of the closely arranged belt portions of the several pairs to travel in different paths and thereby divide the fiber web into a plurality of strips, a slide block arranged adjacent the belts, means for moving the slide block away from the belts and adapted to be moved in the opposite direction at greater velocity, rotatable tubes in said slide blocks, said tubes being adapted to receive the fiber strips, means embodied with said tubes for gripping the fiber strip and retaining it during the movement of the slide block away from the belts and drawing the strip and adapted, during movement of the slide block in the opposite direction to release the strip.
8. In a spinning apparatus for working up material, pairs of coacting belts, each pair including an upper belt and a lower belt, means for guiding portions of each pair of belts in close parallel relation for receiving a fiber web therebetween, the guide means for certain of the pairs of belts being displaced with respect to the guide means of other of said pairs of belts to cause parts of the closely arranged belt portions of the several pairs to travel in different paths and thereby divide the fiber web into a plurality of strips, a rubbing leather and a rubbing roller, said leather and roller being arranged to act upon the fiber strips passing from between the belts, and a slide block draft device and spinning mechanism adapted to act upon the strip passing from the rubbing leather.
9. In a spinning apparatus for working up material, pairs of coacting belts, each pair including an upper belt and a lower belt, means for guiding portions of each pair of belts in close parallel relation for receiving a fiber web therebetween, the guide means for certain of the pairs of belts being displaced with respect to the guide means of other of said pairs of belts to cause parts of the closely arranged belt portions of the several pairs to travel in different paths and thereby divide the fiber web into a plurality of strips, a rubbing roller, a rubbing leather, said roller and leather being arranged to act upon the strips passing from between the belts, a slide block, relatively movable and displaceable rails carried by the slide block, rotatable tubes journaled in said rail having longitudinal bores and cavities in said bores,

4
a strip clamping member having one end pivotally mounted on the tube and the other end arranged to engage the strip in said cavity, the medial portion of said member being arranged between said rails, means for rotating said tubes, stops in the path of the slide block, means for displacing the movable rails upon the slide block coming into

contact with said stops for causing the gripping means to grip the fiber strip in one position of the slide block and for releasing the fiber strip in another position of the slide block.

In testimony whereof I have signed my name to this specification.

MAX MEINKE.
